CLAIM

The ornamental design for a hex ball toy, as shown and described.

DESCRIPTION

FIG. 1 is a perspective view of a hex ball toy in accordance with the present invention.

FIG. 2 is top plan view thereof;

FIG. 3 is a bottom plan view thereof;

FIG. 4 is a right side elevation view thereof;

FIG. 5 is a left side elevation view thereof;

FIG. 6 is a front elevation view thereof; and,

FIG. 7 is a rear elevation view thereof.

The shading is used only to show contrast in the figures. The toy does not require that there be contrast.
